UNITED STATES PATENT OFFICE

CHARLES W. FAILOR, OF FOREST HILLS, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed November 17, 1930, Serial No. 496,109. Renewed October 2, 1931.

My invention relates to railway traffic controlling apparatus for utilizing coded current in track circuits for the control of either or both wayside and cab signals, and more particularly it relates to apparatus for utilizing coded current in the running rails in an absolute permissive block signaling system.

I will describe one form of apparatus embodying my invention, and will then point out the novel features thereof in claims.

The accompanying Figs. 1^a, 1^b, 1^c and 1^d when placed end to end in the order named, with Fig. 1^a on the left form a diagrammatic view showing one form of apparatus embodying my invention when applied to a stretch of single track railway extending between two passing sidings designated in the drawings by the reference characters P¹ and P². In describing my invention, I shall assume the left-hand end of each figure to be west and the right-hand end to be east, and I shall speak of a train traveling from the right to the left as a westbound train and one traveling from the left to the right as an eastbound train. In the following description, reference is made to the accompanying figures wherein like characters of reference designate corresponding parts, the numeral 1 being prefixed to the reference character when the part is associated with westbound traffic and the numeral 2 prefixed to the reference character when the part is associated with eastbound traffic. Also an exponent is added to the reference characters to distinguish the location of the part.

In the accompanying figures, the track rails 1 and 2 are arranged in track sections A—B, B—C and C—D, by the usual insulated rail joints 3. The track sections A—B and C—D are arranged with a cut section at the points A¹ and D¹, respectively, while the section B—C is provided with but a single track circuit. It will be understood that other arrangements of track sections other than that herein described may be employed without departing from the spirit and scope of my invention.

Energy for the operation of part of the apparatus of my invention is supplied by

line transformers L, one of which is located at each junction of adjacent track sections. The primary 4 of each line transformer is connected to a transmission line E which is constantly supplied with alternating current 55 of any convenient frequency such as 60 cycles per second from a source not shown in the drawings.

Line batteries designated by the reference character F are located at the junction of adjacent track sections. These batteries F are each "trickle" charged by a charging unit M each of which includes a transformer 5 and a full-wave rectifier 6. The primary 7 of each of these transformers 5 is permanently connected to the secondary 8 of the associated line transformer L while the secondary 9 of each transformer 5 is connected to the input terminals of the rectifier 6. The output terminals of each rectifier 6 is connected to the terminals of the associated line battery F, all of which will be readily understood by an inspection of the drawings. The line battery F furnishes current for the operation of certain parts of the apparatus of my invention.

At each junction of adjacent track sections there is provided a code transmitter CT which includes a motor element 133 (see Fig. 1^b) constantly supplied with direct current from an associated line battery F. This code transmitter is to be of any of the standard types commonly used in code systems and, as here shown, it will be understood that the two upper contacts 10 and 11 periodically close their respective contacts at the rate of 80 times per minute and that the two lower contacts 12 and 13 periodically close their respective contacts at the rate of 180 times per minute.

Each track section is provided with a track circuit which includes a track relay TR, a track battery TB and two code feeding transformers 1T and 2T. The current supplied to the rails by the track battery TB is constantly coded or periodically interrupted at the rate of 80 or 180 cycles per minute or any other code frequency desired and this coded direct current is utilized for controlling the operation of the track relay. The alternating current supplied to the track circuit under cer-

tain traffic conditions is likewise coded at 80 or 180 cycles per minute or any other desired frequency, and this coded alternating current is utilized to control train-carried devices for 5 governing the operation of cab signals where such train-carried devices are governed by power received inductively from the running rails such, for example, as that disclosed and claimed in the Letters Patent of the United 10 States No. 1,773,472, filed by P. N. Bossart on the 7th day of February, 1927.

The track circuit for section A—A¹ is typical of all track circuits where two track circuits are provided for a track section such as 15 the track sections A—B and C—D, and the track circuit for section A—A¹ is submitted for an understanding of all and is as follows: track battery TBA², resistor unit 14, reactor unit 15, rail 2, wire 16, element 17 of the track 20 relay 2TR^A, wire 18, rail 1, wire 19, secondary 25 20 of the code feeding track transformer 2T^{A1}, wire 21, 180 code contact 12 of code transmitter CT^{A1}, wire 22, normal polar contact 23 of a relay 2H^{A1} to be referred to later, and wire 24 to the negative terminal of the battery TBA². In the event relay 2H^{A1} is reversed the circuit then includes 80 code contact 10 of CT^{A1} and reverse contact 30 of relay 2H^{A1}. The track relay 2TR^A like all track relays of 30 the system is a two-element relay having an element 25 constantly supplied with direct current from the associated line battery 2F^A over the wires 26 and 27, while the second element 17 is connected to the rails 1 and 2 as 35 pointed out above. The track relay 2TR^A, as all the track relays of my invention, is designed to be responsive to direct current code impulses but not to impulses of coded alternating current. It follows that when the section A—A¹ is unoccupied that the track relay 2TR^A is operated at the rate of 180 or 80 40 cycles per minute by current supplied by the track battery TBA² and coded by the code transmitter CT^{A1}.

45 Attention is called to the fact that the track batteries of adjacent track circuits are connected to the rails with reverse polarity as indicated by the plus and minus signs in the figures. Taking location A¹ for illustration, 50 the positive terminal of the battery TBA² is connected to the rail 2 and its negative terminal is connected to the rail 1 while the track battery TBA¹ for the adjacent section A¹—B has its positive terminal connected to the rail 55 1 and its negative terminal connected to the rail 2. Each track relay of the system being a two-element relay, it follows that the reversing of the polarity of the track rails of adjacent track sections provides that full broken 60 down insulated rail joint protection is obtained with the coded track circuits here disclosed.

65 Each track relay controls decoding apparatus including a decoding transformer DT, a rectifier DR and a decoding relay

TP. Looking at track relay 2TR^A of location A for example, the primary 31 of the decoding transformer 2DT^A is supplied with direct current from the associated line battery 2F^A, through the armature 32 of the track relay 2TR^A. When the track relay is energized, current from the positive terminal of the battery 2F^A flows along wire 26, armature 32 in engagement with its front contact, the right-hand half of primary 31 to a center tap, and then by wire 27 to the negative terminal of the battery 2F^A. When the track relay 2TR^A is deenergized and armature 32 is down in engagement with its back contact, the current flows from the battery 2F^A through the left-hand half of primary 31 of the decoding transformer 2DT^A. It follows that with the track relay 2TR^A operated by a coded direct current and its armature 32 alternately in engagement with its front and back contacts 85 that an alternating voltage is induced in the secondary 33 of the transformer 2DT^A, the frequency of which is the same as the frequency of operation of the track relay, and that whenever the track relay 2TR^A remains 90 constantly energized or constantly deenergized, no voltage is induced in the secondary 33. The secondary 33 is connected to the input terminals of the associated rectifier 2DR^A while the associated decoding relay 2TP^A is 95 connected to the output terminals of the rectifier as will be readily understood by an inspection of the Fig. 1^a. The decoding circuit which includes transformer 2DT^A, rectifier 2DR^A, and the relay 2TP^A being non-tuned, it follows that with the track relay 2TR^A being alternately energized and deenergized in step with either the 180 or the 80 code direct current of the track circuit 100 the decoding relay 2TP^A is energized, and that with the track relay constantly energized or deenergized, then the decoding relay 2TP^A is deenergized. At all track sections having but a single track circuit such, for 105 example, as the track section B—C, a track relay is provided at the battery end of the section as well as at the opposite end of the section, and this relay at the battery end has its element 17 connected directly to the track leads. Referring to relay 1TR^C, which is 110 located at the battery end of the section B—C, this relay operates similar to all the other track relays and is associated with a like decoding device. It is to be observed that the track relay for each intermediate section is 115 equipped with a second code following armature.

At all intermediate locations, each decoding relay has associated with it a thermal unit TU, the function of which is to retard the 120 picking up of the decoding relay to thereby insure proper operation of the directional means as will be hereinafter described. These thermal units only come into use when its associated decoding relay is to be energized 125 ...

after it has once been deenergized by virtue of a train shunting the track relay. Taking the thermal unit 1TU^B which is typical of all the thermal units, the following circuit exists for the heating element 34 when the decoding relay 1TP^B is to be energized: battery 1F^B, wire 35, armature 134 of relay 1TR^B, wire 36, heating unit 34, armature 37 of the decoding relay 1TP^B down in engagement with its back contact, and wire 38 back to the battery 1F^B. After a few code impulses, the contact 39 is closed inasmuch as the period required for cooling the heating unit 34 is much longer than the period required for heating the unit. The closing of the contact 39 connects the wire 40 leading from the center tap of the decoding transformer 1DT^B to the wire 38 leading to the negative terminal of the battery 1F^B. This completes the circuit from the primary 31 of the decoding transformer 1DT^B which allows decoding relay 1TP^B to be energized. With relay 1TP^B energized, the circuit for the heating unit 34 is opened at the back contact of the armature 37 and wire 40 is connected to the negative wire 38 at the front contact of the armature 37.

With each decoding relay there is associated a direct current polarized line relay and a slow-releasing line repeater relay designated by the reference characters H and HP, respectively. Looking at line relay 1H^D, the circuit for energizing this relay may be traced from the positive terminal of the battery 1F^C, wire 41, front contact 42 of the line repeater relay 1HP^C, wire 43, front contact 44 of the decoding relay 2TP^C, line wire 45, front contact 46 of the decoding relay 1TP^D, winding of relay 1H^D, line wire 47, front contact 48 of relay 1HP^C, and wire 49 to the negative terminal of the battery 1F^C. It will be observed that with the repeater relay 1HP^C deenergized, thereby closing its back contacts 50 and 51, and with a directional relay 1V^C energized, in a manner to be later described, to thereby close its front contact 52, then the current supplied by the battery 1F^C to the circuit just traced for the line relay 1H^D is reversed in polarity. When the line relay 1H^D is energized with normal polarity of current, its polar armature 53 occupies the left-hand position, that is, the position as shown in Fig. 1^d, and when it is energized with reverse polarity of current, the polar armature 53 is reversed to the right-hand position. The repeater relay 1HP^D is controlled by its associated line relay 1H^D and is energized by a local circuit from the battery 1F^D as follows: wire 54, front contact 55 of line relay 1H^D, relay 1H^D, and wire 56 to the negative terminal of the battery 1F^D. Each line relay and its associated repeater relay located at each junction of adjacent track sections is controlled in the same manner as just described for the relays 1H^D and 1HP^D. At each cut section,

such as locations A¹ and D¹, a polarized line relay H is also provided for each track circuit and each line relay is connected in parallel with the controlling line relay H associated with the respective track circuit and located at the track relay end of the section. Looking at location D¹, the polarized line relay 1HD¹ has one terminal connected to the line wire 45 by a wire 57 and its other terminal is connected to the line wire 47 by a wire 58, and thus this relay 1HD¹ is energized whenever the line circuit for relay 1H^D is closed.

At the junction of adjacent intermediate track sections there is provided the usual directional stick relay commonly used in absolute permissive block signaling systems and which is here designated by the reference character V with proper exponents. This stick relay performs similar functions as that of the directional stick relay used in standard absolute permissive block systems, that is, to establish directional control and to provide for following train movements. As the circuits for selecting the directional stick relay are alike for all such relays, it is deemed sufficient to describe but one in detail for an understanding of all. Taking relay 2V^C for illustration, this relay has a pick-up circuit as follows: battery 2F^C, wire 59, back contact 60 of the opposing directional relay 1V^C, wire 61, back contact 62 of the repeater relay 1HP^C, wire 63, back contact 64 of the decoding relay 1TP^C, wire 65, back contact 67 of the decoding relay 2TP^C, wire 68, front contact 69 of the repeater relay 2HP^C, wire 70, coil of relay 2V^C, and wire 71 to the negative terminal of the battery 2F^C. Once this directional stick relay 2V^C is energized then it is held energized by a stick circuit branching from the positive wire 59, through back contact 72 of relay 2H^C, wire 73, its own front contact 74 to the wire 70, coil of the relay 2V^C, and wire 71 to the negative terminal of the battery 2F^C.

Each track section is provided with a wayside signal located at each end of the section to govern traffic in opposite directions through the section. Signals governing westbound traffic are designated by the reference character 1S and the signals governing eastbound traffic are designated by the reference character 2S. These wayside signals may be of any of the standard types and are here shown as three-position light signals. The lighting circuits of each signal are controlled by the associated line relay and line repeater relay, and as the circuits of all signals are alike, a description of any one will be sufficient for the understanding of all. Referring to the signal 2S^D, the proceed signal light circuit extends from one terminal of the secondary 8 of the associated line transformer L^D, wire BX110, wire 75, back contact 76 of the opposing line

repeater relay 1HP^D, wire 77, front contact 78 of the associated repeater relay 2HP^D, polarized armature 82, normal polar contact 79 of the associated line relay 2HD, wire 80, 5 proceed light 81, and wire CX110 to the common terminal of the secondary 8. The approach signal light circuit is the same as the proceed light circuit up to the polar armature 82 of the line relay 2HD, then with 10 armature 82 reversed so as to be in engagement with the reverse contact 83, the circuit extends along wire 84, approach signal light 85, and the CX110 wire to the common terminal of secondary 8. The stop signal light 15 circuit branches from the wire 77 to the back contact 86 of the associated repeater relay 2HP^D, wire 87, stop signal light 88, and the common return wire CX110.

At each siding location there is provided a 20 pole-changing relay designated by the reference character HD, and this relay is controlled by the line relay of the same location. Referring to the relay 1HD^A located at the siding P¹, this relay is energized by a circuit 25 from the positive terminal of the battery 1F^A, wire 126, front contact 127, polar contact 128, winding of relay 1HD^A, and wire 129 back to the battery 1F^A. The relay 2HD^D located at the siding P² is governed by a similar circuit.

30 As stated earlier in the specifications, two code feeding track transformers are provided for each track circuit, one located at each end of the track section. Through the medium of these transformers, coded alternating current is fed to the track rails for the purpose of controlling train-carried cab signal devices such as shown in the United States Letters Patent No. 1,773,472 heretofore mentioned. At the battery end of the track circuit, the secondary of the code feeding transformer is connected in series with the track battery, while at the relay end of the track circuit, the secondary of the code feeding transformer is connected in parallel with the 45 track element of the track relay. The track circuit for section A—A¹ is typical of all, and, as previously traced, the track circuit of this section includes the secondary 20 of the code feeding transformer 2T^{A1}. At the relay end 50 of the section A—A¹, the secondary 28 of the code feeding transformer 1T^A is connected in parallel with the track element 17 of the track relay 2TR^A and in series with the resistor 29. The primary 89 of the transformer 2T^{A1} is 55 supplied with alternating current from the secondary 8 of the line transformer L^{A1} over wire BX110, wire 90, front contact 91 of the associated line relay 2H^{A1}, back contact 92 of the opposing line relay 1H^{A1}, wire 93, primary 60 89, wire 94, and wire CX110 to the other terminal of the secondary 8. This primary circuit being normally open at the back contact 92 of the opposing line relay 1H^{A1}, train governing energy is only supplied by it to the 65 track circuit during the period an eastbound

train is occupying the section. Inasmuch as the secondary circuit of 2T^{A1} is periodically interrupted at 80 or 180 times per minute, the rate depending upon the position of the polar armatures of the line relay 2H^{A1}, it is apparent that whenever the primary 89 is energized with alternating current that the secondary 20 supplies coded alternating current to the track rails. The primary 95 of the code feeding transformer 1T^A has a circuit as 70 follows: secondary 8 of the line transformer L^A, wire BX110, wire 96, 180 code contact 13 of code transmitter CT^A, wire 97, front contact 98 of line repeater relay 1HP^A, wire 99, back contact 100 of the opposing line relay 2H^A, wire 101, primary 95, wire 102, and wire CX110 to the common terminal of the secondary 8. It is thus apparent that whenever this circuit from the primary 95 is closed by a westbound train, that 180 coded alternating current is fed to the rails of the section A—A¹ by the secondary 28. The primary 95 is supplied with 80 code alternating current in the event the line relay 1H^A is 80 de-energized and a circuit is established which 85 branches from the wire 96 through the 80 code contact 11 of the code transmitter CT^A, wire 103, back contact 104 of the line repeater relay 1HP^A, and then as before traced for the 90 180 code current. At all intermediate locations, the 180 code alternating current is supplied in a like manner as that described for the track section A—A¹, however, the 80 code alternating current is controlled by the directional relay at the intermediate signals. 95 Taking location B for example, the circuit for supplying 80 code alternating current to the primary 105 of the code feeding transformer 1T^B is from the secondary 8 of the line transformer L^B, wire BX110, wire 106, 100 80 code contact 10 of the code transmitter CT^B, wire 107, front contact 108 of the directional relay 1V^B, back contact 109 of the line repeater relay 1HP^B, wire 110, back contact 111, wire 112, primary 105, and wire CX110 to the common terminal of the secondary 8. 110

Having pointed out the various circuits and apparatus with which each track section is provided, I shall now describe the operation of the system and I shall first assume that each track section between the two passing sidings P¹ and P² is unoccupied. As described earlier in the specifications, each track circuit is constantly supplied with either 180 code or 80 code direct current and this coded direct current operates the track relay. It was also pointed out that the positive terminal of the F battery was connected to the heel of the 32 armature of the track relay and that the extreme ends of the primary of the decoding transformer are connected to the front and back contacts of the armature 32, while the center tap of the primary is connected to the negative terminal of the battery 125 130

F. Therefore, with armature 32 alternately closing the front and back contacts in step with either 180 or 80 code direct current, the half of the primary winding of the decoding 5 transformer fed by the front contact will be energized during the "on" code period building up a flux in one direction, and when the "off" period of the code occurs, then the back contact closes, and the other half of the primary 10 31 will be energized in a reverse direction from that of the first. This action will cause a flux to build up in one direction and to die down and build up in the reverse direction with each 180 or 80 code cycle. With the 15 building up of the flux in one direction and the dying down and building up in the opposite direction, a voltage is induced in the secondary 33 having a corresponding frequency. The secondary 33 is connected to the input 20 terminals of the rectifier DR to whose output terminals the decoding relay TP is connected, thus the relay TP is normally energized. With the decoding relay TP held closed then 25 the associated line relay and, in turn, the line repeater relay are both normally energized. It is recalled that when the various circuits were traced it was shown that with the line relay and its associated line repeater relay both energized, the proceed operating circuit 30 for the associated wayside signal is closed to govern the operation of the signal. Also that the operating circuits for the wayside signals at each location, except at the leaving signal at each siding, are held open at a back contact 35 of the opposing line repeater relay to act as an approach lighting means for the wayside signals. Furthermore, with the line relay and its line repeater relay both closed, the circuit for the associated code feeding transformer 40 is set to supply a coded alternating current to the rails, the circuit however, is held open at a back contact of the opposing line relay to act as an approach energizing means for the code feeding transformer. Thus normally 45 the track circuits are supplied with 180 code direct current, the leaving signal at each siding displays a proceed signal, the line control relays are each normally energized and each arranged to approach light an opposing 50 intermediate signal and to approach energize the track circuit of the associated section with train governing coded alternating current.

Describing next the operation of the apparatus for an eastbound train and assuming 55 that an eastbound train occupies the track section to the left of location A and that all the intermediate track sections up to the passing siding P² are unoccupied. With the train occupying the section to the left of location A, 60 the track relay 1TR^A is shunted and thereby the associated relays 1TP^A, 1H^A, 1HP^A and 1HD^A are all deenergized with the result that the stop light circuit of the signal 1S^A is closed at the back contact 116 of the relay 65 1HP^A and signal 1S^A set to display a stop

signal to any approaching westbound train. The current for the line relays 1H^{A1} and 1H^B is reversed from the normal polarity at the back contacts of armatures 113 and 114 of the 70 1HD^A relay, resulting in the approach signal light circuit of signal 1S^B being closed at the reverse contact 115 of the line relay 1H^B and signal 1S^B set to display an approach signal to any approaching westbound train. With line relay 1H^{A1} at the cut section A¹ reversed, 75 then 80 code direct current is fed to the track circuit of the section A¹—B. However, inasmuch as the track relay 1TR^B is responsive to 80 code direct current as well as to 180 code direct current and inasmuch as the decoding circuit is non-tuned, the decoding relay 1TP^B remains energized. With the line relay 1H^A down to close the back contact 132, 180 code alternating current is supplied to the code feeding transformer 2T^A and thus the rails 80 of the section in advance of the train are fed with 180 code alternating current to affect the train carried cab signals.

As the train advances to the east and enters section A—B, the first pair of wheels shunts the track relay 2TR^A and, in turn, the relays 2TP^A, 2H^A and 2HP^A all become deenergized and the signal 2S^A set to display a stop signal. The line circuit to the line relay 1H^B is now open at the contact 117 of the relay 2TP^A and the relays 1H^B and 2HP^B at the location B are deenergized and the opposing signal 1S^B set to display a stop signal. Likewise the line circuit for each successive opposing westbound signal up to the passing siding P² is open at the line repeater relay in advance, and each opposing signal set to display a stop signal to any westbound train. It is to be noted that at locations A¹ and D¹, the line relays 1H^{A1} and 1H^{D1}, respectively, are now deenergized, however, these polarized relays are such that their polar contacts 23 are held closed with sufficient contact pressure to retain the respective track circuit in its normal condition even with the relay deenergized. At the location A¹, the line relay 1H^{A1} being down and the line relay 2H^{A1} up, alternating current is fed to the primary 89 of the code feeding transformer 2T^{A1}. The alternating current induced in the secondary 20 by the alternating current in the primary 89 is coded by the 180 code contact 12 of the code transmitter CT^{A1}, and thus the train carried devices are influenced by 100 180 code alternating current as the train 105 travels the section A—A¹.

The train upon passing the cut section A¹ and entering the section A¹—B shunts the track relay 1TR^B and its associated relays are deenergized. The line circuit for the line relay 2H^A being now open at the contact 118 of the relay 1TP^B, the signal 2S^A is still held at stop even after the rear of the train vacates the section A—A¹ and the decoding relay of that section reenergized. The line 110 115 120 125 130

relay $1H^B$ being down to close the back contact 123, 180 code alternating current is fed to the primary 124 of the code feeding transformer $2T^B$ by a circuit similar to that traced for primary 95 of $1T^A$ and the rails of the section A^1-B are supplied with 180 code alternating current to influence the train carried cab signals of the eastbound train. The line repeater relay $1HP^B$ being open, the back contact 130 is closed and current is supplied to the proceed light circuit of the signal $2S^B$ to thereby display a proceed signal to the eastbound train.

As the train enters the section $B-C$ and shunts at track relay $2TR^B$ to thereby deenergize its associated relays, the signal $2S^B$ is set to display a stop signal. The relay $2HP^B$ being slower to release than the decoding relay $2TP^B$, the pick-up circuit for the directional relay $2V^B$ is momentarily closed to energize this relay, after which it is retained energized by its stick circuit. The opposing line relay $1H^C$ being down, alternating current is supplied to the primary of the code feeding transformer $2T^C$. The alternating current induced in the secondary of transformer $2T^C$ is coded by the 180 code contact 13 of the code transmitter CT^C and thus the train carried cab signals are influenced by 180 code alternating current as the train travels the section $B-C$. The line repeater relay $1HP^C$ being open, its back contact 131 is closed and current supplied to the proceed light circuit of the signal $2S^C$ to display a proceed wayside signal to the eastbound train. The energizing of the directional relay $2V^B$ results in the line circuit for the line relay $2H^A$ being supplied with current of reverse polarity as soon as the train vacates the section A^1-B , and the track relay $1TR^B$ and its decoding relay $1TP^B$ become reenergized. With the line relay $2H^A$ and likewise the relay $2H^{A1}$ energized by current of reverse polarity, the line repeater relay $2HP^A$ is reenergized and thus the signal $2S^A$ is set to display an approach signal. The line circuit to the rear of location A will now be energized by current of normal polarity and thus the eastbound signal to the rear of $2S^A$ will be set to display a proceed signal. As the train vacates the section A^1-B and its decoding relay $1TP^B$ reenergized, the circuit for the westbound signal $1S^B$ is restored to its normal condition. With the line relay $2H^{A1}$ reenergized by current of reverse polarity, 80 code direct current is supplied to the track circuit of the section $A-A^1$, but inasmuch as the track relay is responsive to 80 code direct current as well as to 180 code direct current, and inasmuch as the decoding circuit is non-tuned, the decoding relay $2TP^A$ is energized.

Assuming a following eastbound train passes the approach signal $2S^A$ while the first train occupies the section $B-C$, it is apparent that the track circuit for section

$A-A^1$ is supplied with 80 code current through the contact 10 of the code transmitter CT^{A1} , and thus 80 code alternating current is supplied to the track circuit of section $A-A^1$ to influence the train carried devices of this following train. In the event the following train advances and enters the section A^1-B , while the first train occupies section $B-C$, we find that 80 code alternating current is supplied to the code feeding transformer $2T^B$ by the following circuit: secondary 8 of transformer L^B , wire $BX110$, wire 106, 80 code contact 11 of CT^B , wire 119, front contact 120 of directional relay $2V^B$, back contact 121 of the repeater relay $2HP^B$, wire 122, back contact 123 of $1H^B$, primary 124, and wire $CX110$ to the common terminal of secondary 8. Thus 80 code alternating current is supplied to the rails of the section A^1-B to influence the train carried cab signals of this following train.

As the train leaves the section $B-C$, coded direct current again operates the track relay $2TR^B$ and the relays $2TP^B$, $2H^B$ and $2HP^B$ are reenergized, and the stick circuit for the directional relay $2V^B$ is opened at the back contact 125 of relay $2H^B$ thereby restoring the directional relay to its normal position.

In the event there should occur a momentary loss of train shunt while the train occupies the section $B-C$, and the track relay $2TR^B$ operated by a few code impulses of direct current, the decoding relay $2TP^B$ will not pick up until such time as the associated thermal unit $2TU^B$ functions to close its contact, and in view of this delay in the picking up of the relay $2TP^B$, the associated line relay will not pick up during this short momentary loss of the train shunt. This delay in reenergizing the line relay prevents a momentary loss of train shunt from deenergizing the directional relay $2V^B$ with a result of loss in directional control.

As the first eastbound train advances and enters the successive track sections, the operation of the apparatus is the same as that described for the sections $A-B$ and $B-C$. Also the operation of the apparatus for a westbound train is similar to that described for eastbound traffic.

Such a system herein disclosed and described is practically immune of propulsion alternating current or propulsion direct current or any other form of electrical energy that may be used in the running rails. The track relays respond readily to coded direct current requiring thereby low energy output of the track battery. While the disclosure shows a system wherein the train governing coded alternating current is fed to the track circuits directly from the transmission line, it will function equally as well for a system that provides a motor driven alternator wherewith current from the line battery is used, as a standby apparatus to insure con-

tinuous operation of the cab signals during periods of loss of power on the transmission line.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a track section, a track circuit including the traffic rails of the section, a source of current to normally supply the track circuit with current of a given character periodically interrupted, a second source of current to supply the track circuit with train-governing current of a different character periodically interrupted, a track relay connected to the track circuit responsive to the periodically interrupted current of said given character and not responsive to the periodically interrupted current of said different character, a wayside signal, and means controlled by the track relay to govern the operation of the wayside signal and to control the supply of periodically interrupted train-governing current of said different character to the track circuit of another track section.

2. In combination, a track section, a track circuit including the traffic rails of the section, a source of current to normally supply the track circuit with direct current periodically interrupted, a second source of current to supply the track circuit with train-governing alternating current periodically interrupted, a track relay connected to the rails and normally responsive to the periodically interrupted direct current but not responsive to the periodically interrupted alternating current, a wayside signal, and means controlled by the track relay when operated by the interrupted direct current to govern the operation of the wayside signal and to control the supply of periodically interrupted train-governing alternating current to the track circuit of another track section.

3. In combination, a track section, a track circuit including the traffic rails of the track section, a source of current to normally supply to the rails coded direct current, a second source of current to supply to the rails train-governing coded alternating current, a track relay connected to the traffic rails and normally responsive to the coded direct current but not responsive to the coded alternating current, a decoding relay, means to energize said decoding relay with the track relay operated by coded direct current, a wayside signal to govern traffic through the section, and means controlled by the decoding relay to govern the operation of the signal and to

control the supply of train-governing coded alternating current to the track circuit of another track section.

4. In combination, a track section, a track circuit including the traffic rails of the section, a source of current to normally supply to the rails coded direct current, a second source of current to supply to the rails train-governing coded alternating current of different codes, a track relay connected to the traffic rails and normally responsive to the coded direct current but not responsive to the coded alternating current, a decoding relay, means to energize said decoding relay with the track relay operated by coded direct current, a wayside signal, and means controlled by the decoding relay to govern the operation of the signal and to selectively control the different codes of the train-governing coded alternating current supplied to the track circuit of another track section.

5. In combination, a track section, a track circuit including the traffic rails of the section, a source of normally active direct current and a source of normally inactive alternating current for the track circuit and said sources connected in series across the traffic rails, means to periodically interrupt the connection to the rails to establish a normal flow of periodically interrupted direct current in the rails, a track relay connected to the rails and responsive to the interrupted direct current, a wayside signal, and a circuit controlling device energized in response to the track relay operated by the interrupted direct current to govern the operation of the signal and said device deenergized in response to the track relay shunted to render effective the source of alternating current to thereby establish a flow of train-governing periodically interrupted alternating current in the rails.

6. In combination, a track section, a track circuit including the traffic rails of the section, a source of normally active direct current and a source of normally inactive alternating current and said sources connected in series across the traffic rails of the section, means to periodically interrupt the connection to the rails to establish a normal flow of periodically interrupted direct current in the rails, a track relay connected to the rails and responsive to the interrupted direct current, a circuit controller held in one given position in response to the track relay operated by the interrupted direct current and held in a second given position with the track relay shunted, and means controlled by the circuit controller in the first given position for controlling the source of alternating current of another track section and said means to render active the source of alternating current of the track section when the circuit controller occupies the second given position.

7. In combination, a track section, a track

- 5 circuit including the traffic rails of the section, a source of normally active direct current and a source of normally inactive alternating current for the track circuit, a plurality of paths for connecting said sources in series across the traffic rails, traffic controlled means for selectively closing one of said paths, means to periodically interrupt each of said paths at a different rate, a track relay 10 connected to the rails and responsive to periodically interrupted direct current, a wayside signal, and a circuit controlling device energized in response to the track relay operated by interrupted direct current of any one 15 of said different rates to govern the operation of the signal, and said device deenergized in response to a train entering the section to render effective the source of alternating current to thereby establish a flow of 20 train-governing periodically interrupted alternating current in the rails at a rate corresponding to traffic conditions.
8. In combination, a track section, a track circuit including the traffic rails of the track 25 section, means for normally supplying the track circuit with current periodically interrupted, a track relay connected across the traffic rails and responsive to such periodically interrupted current, a decoding relay, 30 means to energize the decoding relay in response to the track relay operated by the interrupted current, means effective with the decoding relay deenergized to prevent the reenergizing of the decoding relay until after 35 the track relay has been operated for a given interval by the interrupted current, and means for signaling controlled by the decoding relay.
9. In combination, a track section, a track 40 circuit including the traffic rails of the track section, means for normally supplying the track circuit with current periodically interrupted, a track relay connected across the traffic rails and responsive to such periodically 45 interrupted current, a decoding relay, means to energize the decoding relay in response to the track relay operated by the interrupted current, and said thermal relay to close its contact after a given time interval 50 in response to current impulses produced therein by the track relay operated by the interrupted current, and said thermal relay effective with the decoding relay deenergized to prevent the reenergizing of the decoding 55 relay until the track relay has been operated the said given time interval.
10. In combination, traffic rails arranged 60 in track sections, a track circuit for each track section, a source of coded direct current for each track circuit and so connected to the traffic rails that the rails of adjacent track sections are of reverse polarity, a two-element track relay for each track circuit having one element constantly energized by direct 65 current of a given polarity and the second

element connected to the traffic rails and energized by the coded direct current of the polarity of the associated track circuit, and a circuit controlling armature for said relay operated on code only when the two elements are energized with proper polarity to thereby provide detection of a break down of the insulation of the insulated rail joints separating the track sections. 70

11. In combination, a stretch of traffic rails over which traffic may move in either direction, a wayside signal located at each end of the stretch to govern traffic in opposite directions through the stretch, a normally inactive source of train-governing current located at each end of the stretch each adapted to supply coded alternating current across the traffic rails at its respective end of the stretch to govern traffic in opposite directions, a normally active source of track circuit current to supply across the traffic rails coded direct current, a track relay connected to the rails and responsive to the coded direct current in the rails, a decoding relay, means to energize the decoding relay in response to the operating of the track relay by the coded direct current, and means controlled by the decoding relay to govern the operation of the wayside signals and to render effective the sources of train-governing current. 75 80 85 90 95

12. In combination, a stretch of traffic rails over which traffic may move in either direction, a wayside signal located at each end of the stretch to govern traffic in opposite directions through the stretch, a normally inactive source of train-governing current located at each end of the stretch each adapted to supply coded alternating current across the traffic rails at its respective end of the stretch to govern traffic in opposite directions, a normally active source of track circuit current to supply across the traffic rails coded direct current, a track relay connected to the rails and responsive to the coded direct current in the rails, a decoding relay, means to energize the decoding relay in response to the operating of the track relay by the coded direct current, traffic directional means responsive to the direction of traffic, and means controlled jointly by the decoding relay and the traffic directional means to selectively govern the operation of the wayside signals and to selectively render effective the sources of train-governing current. 100 105 110 115 120

13. In combination, a stretch of traffic rails over which traffic may move in either direction, a wayside signal located at each end of the stretch to govern traffic in opposite directions through the stretch, a normally inactive source of train-governing current located at each end of the stretch each adapted to supply coded alternating current of different codes across the traffic rails at its respective end of the stretch to govern traffic in opposite directions, a normally active source of 125 130

track circuit current to supply across the traffic rails coded direct current, a track relay connected to the rails and responsive to the coded direct current in the rails, a decoding relay, means to energize the decoding relay in response to the operating of the track relay by the coded direct current, means controlled by the decoding relay to govern the operation of the signals and to render effective the sources of train-governing current, and means responsive to traffic conditions of another section to select the code supplied by the sources of train-governing current.

14. In combination, a stretch of traffic rails over which traffic may move in either direction arranged in two track sections, a track circuit for each track section, a normally active source of coded direct current and a normally inactive source of train-governing coded alternating current of different codes for each track circuit with said sources located at the adjacent ends of the track sections, a track relay for each track circuit located at the remote ends of the sections and each responsive to coded direct current, a decoding relay for each section, means associated with each track relay to energize the decoding relay in response to the track relay operated by the coded direct current, a polarized line relay for each section located at the adjacent ends of the sections to selectively render effective the sources of coded alternating current and to select the different codes, and a line circuit for each line relay controlled by the decoding relay of the section with which the line relay is not associated and by traffic conditions of another track section.

15. In a combined wayside and cab signal system, traffic rails arranged in track sections, a track circuit for each track section, a wayside signal for each section, a first current source for each section adapted to supply to the track circuit train-governing coded alternating current of different codes, a second current source for each section adapted to constantly supply to the track circuit coded direct current, a track relay for each track circuit responsive to coded direct

50 current but not responsive to coded alternating current, a decoding relay for each section, means associated with each track relay to energize the decoding relay in response to the track relay operated by the coded direct current, and means controlled by the decoding relay to govern the operation of the wayside signal and to select the code of the train-governing alternating current supplied to the track circuit for the track section in the rear.

60 16. In a combined wayside and cab signal system, traffic rails arranged in track sections, a track circuit for each track section, a wayside signal for each section, a first current source for each section adapted to supply to the track circuit train-governing

coded alternating current of different codes, a second current source for each section adapted to constantly supply to the track circuit coded direct current, a track relay for each track circuit responsive to coded direct 70 current but not responsive to coded alternating current, a circuit controller associated with each track relay retained in one given position in response to the track relay operated by the coded direct current and retained in a second given position when the track relay is shunted, and circuits controlled by the circuit controller to govern the operation of the wayside signal and to select the code of the train-governing alternating current supplied to the track circuit for the track section to the rear.

17. In a combined wayside and cab signal system, a stretch of single track railway arranged in track sections, signals located at each end of the stretch to govern traffic in opposite directions through the stretch, a normally inactive source of alternating current located at each end of each track section adapted to supply train-governing coded alternating current to the traffic rails at its respective end of the section to govern traffic in opposite directions through the section, a normally active source of direct current for each section adapted to supply coded direct 95 current to the traffic rails, a track relay for each section responsive to coded direct current but not to coded alternating current, a decoding relay for each section, means associated with each track relay to energize the decoding relay in response to the track relay operated by the coded direct current; and means controlled by the decoding relays, in response to a train entering the stretch at either end, to set at stop the opposing signal, 100 to open the circuit of each source of coded alternating current governing traffic in the opposing direction, and to render effective each source of coded alternating current governing traffic in the same direction as that 110 of the train entering the stretch.

In testimony whereof I affix my signature.
CHARLES W. FAILOR.
